ATTORNEYS

UNITED STATES PATENT OFFICE.

CHARLES R. HADLEY, OF LOS ANGELES, CALIFORNIA; FRANK D. BARNHILL AND PACIFIC SOUTHWEST TRUST & SAVINGS BANK, EXECUTORS OF SAID CHARLES R. HADLEY, DECEASED, ASSIGNORS TO CHARLES R. HADLEY COMPANY, OF LOS ANGELES, CALIFORNIA, A CORPORATION OF CALIFORNIA.

POSTING STAND.

Application filed September 25, 1922. Serial No. 590,226.

To all whom it may concern:

Be it known that I, CHARLES R. HADLEY, a citizen of the United States, residing at Los Angeles, in the county of Los Angeles and State of California, have invented a new and useful Posting Stand, of which the following is a specification:

This invention relates to posting stands of the type employed in machine book keeping, 10 and is more especially adapted for use in posting alphabetically.

An object of the invention is to provide a stand of this type that will function to produce the desired results in a manner that 15 will facilitate the various operations so as to expedite the posting of accounts.

The accompanying drawings illustrate the invention:

Fig. 1 is a perspective view of a posting 20 stand embodying the provisions of this invention.

Fig. 2 is a plan view of the stand shown in Fig. 1, the movable guide being in closed position in solid lines and being indicated 25 in open position in broken lines.

Fig. 3 is a perspective detail of the movable guide and adjacent parts.

Fig. 4 is a detail of the movable guide and the adjacent portion of one of the binder 30 covers to show the interlocking therebetween, the guide being shown in cross section.

Fig. 5 is an enlarged plan section of the lock for the movable guide with the guide 35 in closed position therein.

Fig. 6 is a detail, partly in section, showing the adjustment feature of the guides.

A suitable frame, indicated at 10, is provided, and mounted on opposite sides of the 40 frame are standards 11. Fastened at their opposite ends to the ends of the frame 10 are spaced parallel W-shaped members 12 positioned along opposite sides of the frame.

Intermediate their ends the members 12 are 45 secured to the standards 11. Mounted on the intermediate portions of the members 12 is an inverted V-shaped member 13. The members 12, 13 together constitute a binder support. When in use, as clearly shown in 50 Figure 1, one cover 14 of the binder rests aslant outwardly and upwardly on one portion of the support 12, 13, and the other

cover 15 rests aslant in the opposite direction on said support with the member 13 extending between said covers.

The leaves 16 of the binder may be positioned adjacent either of the covers 14, 15 with their side margins flush, or said leaves may be offset in a manner well understood in accountancy. When the leaves 16 are in 60 register, as shown in Figure 1, one edge of the pack of leaves engages a guide 17, the intermediate portion of which is of inverted V-shape to correspond in angularity with the support member 13.

The end portions 18 of the guide 17 are bent at right angles from the intermediate portion of said guide and are inserted in a sleeve or tubular way 19. The end portions 18 are provided with notches 20 and, adapted to selectively engage said notches according to the adjustment of the guide 17, there are screws 21 which are threaded through the frame 10 and project through the walls of the sleeves so as to hold the 75 guide in the adjusted position. The ends of the sleeves 19 engage holes 22 in the frame 10 and are headed over, as indicated at 23, on the outer face of the frame so as to secure said sleeves in place.

Slidably engaging the other ends of the sleeves 19 are adjustable members 24, which are provided with notches 25 that are adapted to be selectively engaged by screws 26 threaded through the frame 10 and projecting through the walls of the sleeves. The outer ends of the members 24 are pivoted at 27 to the opposite ends of a movable guide 28, said guide being approximately inverted V-shaped so as to conform in angularity with the member 13. The guides 17, 28 are in parallelism and are in the form of rods. One of the members 24 terminates at its outer end in a fork or up-turned channeled portion 29, the vertical channel 95 being indicated at 30. When the guide 28 is in closed position, as in Figure 1, a vertical portion 31 of said guide engages the channel 30.

Opposite portions of the wall of the channel 30 are perforated as indicated at 32, to accommodate locking means in the form of ball detents 33, the inner ends of the perforations being of less diameter than the balls

so that the balls cannot roll into the channel. The fork 29 is provided in its outer face with a semi-circular groove 34, and engaging said groove is a U-shaped spring 35 having outwardly curved portions 36 engaging the outer faces of the balls 33, said balls being of greater diameter than the thickness of the wall of the fork 29 so that one side of each ball will engage the guide 28 while the other side engages the spring. The spring 35 thus tends to yieldingly hold the balls 33 inwardly so that when the guide 28 is in closed position, as in Figure 5, said guide cannot be opened without the application of sufficient force to expand the spring 36.

It will be clear from the foregoing that both guides 17, 28 are movable toward and from the binder because of the provision of 20 the sleeves 19; that the guide 28 is also movable because of it being hingedly connected with the frame; that the screws 21 hold the guides in different positions of adjustment; that the guide 28 is releasably held in binder- 25 engaging position by the locking elements 33 and springs 35; and that the guides are angled to parallel the intermediate portion of the support.

The binder covers 14, 15, may be of any 30 suitable construction excepting that the longitudinal edges thereof are provided with notches 37 which are engaged by the guides 17, 28 when the covers are in correct posting position on the stand, as in Figure 1. In the 35 instance shown the covers 14, 15 are each constructed in two sections hinged together at 38 in a manner well understood in the art pertaining to loose leaf binders, and the notches are in the shorter sections 39 adjacent the longer sections 40 so that the guides 40 will support the longer sections and prevent the shorter sections from crowding the leaves 16 out of place.

In practice, the binder covers being in 45 closed position, and it being desired to place the binder on the stand, the guide 28 will be thrown into the broken line position indicated at *a* in Figure 2 and the binder will be placed on the support 12 with the cover member 13 in the position shown in Figure 50 1. Then the guide 28 will be swung to the closed position. When said guide 28 is closed, both it and the guide 17 should be in engagement with the notches 37 of the binder 55 covers, and by properly adjusting the guides in the sleeves 19 such result can be readily achieved. Then the binder posts 41, well known in the art pertaining to binders, will be released and the binder cover 15 will be 60 shifted along the guides 17, 28 to the position shown in Figure 1.

Then the posting operations will be per-

formed in a manner well understood in accountancy and, if desired, the leaves that have been posted may be offset so as to engage the guide 28. The guide 28 thus aligns the offset leaves the same as the guide 17 aligns those leaves that are not offset. After the posting operations are completed, the binder may be closed and detached from the stand by a reversal of the operations above described, so that the offset arrangement of the leaves can be retained as long as desired.

It will now be understood that by the construction described above the binder is securely attached to the stand when the guide 28 is closed, making it impossible to accidentally knock the binder covers and leaves off of the stand. Correct posting and locking positions of the binder covers are asured because of said covers sliding into the different positions along the guide.

I claim:

1. In a posting stand, the combination of a base, means on the base to support loose 85 leaves edgewise thereon, and means mounted on the base to support the upper section of the hingedly connected sections of a binder cover edgewise above said means to prevent folding of said sections at the hinge.

2. In a posting stand, the combination of a base, a support mounted on the base to receive a loose leaf binder, a guide connected with one side of the base, members mounted in the base to shift laterally with respect thereto, an inverted substantially V-shaped guide pivoted at its ends to said shiftable members, means to hold the shiftable members in different positions of adjustment, and means to releasably hold the pivoted guide 100 in position to engage a binder placed on the stand.

3. In a posting stand, the combination of a base, leaf-supporting means on the base, members adjustably connected with the base, a movable guide at one side of the leaf-supporting means hinged at its opposite ends to the respective adjustable members, and means to releasably hold the guide in position to be engaged by leaves on the leaf- 110 supporting means.

4. In a posting stand, the combination of a base, a support mounted on the base to receive a loose leaf binder, members mounted in the base to shift laterally with respect thereto, a guide pivoted at its ends to said shiftable members, means to hold the shiftable members in different positions of adjustment, and means to releasably hold the pivoted guide in position to engage a binder 120 placed on the stand.

Signed at Los Angeles, California, this 11th day of September, 1922.

CHARLES R. HADLEY.
